UNITED STATES PATENT OFFICE.

EVERETT P. RICHARDSON, OF LAWRENCE, MASSACHUSETTS, ASSIGNOR OF ONE-HALF TO JOHN H. RICHARDSON, TRUSTEE, OF LAWRENCE, MASSACHUSETTS.

PRESSER-FOOT MECHANISM FOR SHOE-SEWING MACHINES.

SPECIFICATION forming part of Letters Patent No. 710,613, dated October 7, 1902.

Original application filed June 21, 1900, Serial No. 21,084. Divided and this application filed April 25, 1901. Renewed January 20, 1902. Serial No. 90,476. (No model.)

To all whom it may concern:

Be it known that I, EVERETT P. RICHARDSON, of Lawrence, in the county of Essex and State of Massachusetts, have invented certain new and useful Improvements in Shoe-Sewing Machines, of which the following is a specification.

This invention has relation to machines for sewing soles to the uppers of boots and shoes, being more particularly related to that class known as "McKay" sewing-machines, in which the needle penetrates the sole and enters the interior of the shoe, and a horn is introduced into the shoe to support the latter and to carry the complementary sewing mechanism which co-operates with the needle in forming the stitches.

The object to be attained by the invention is the provision of improved mechanism for automatically regulating the operation of the presser-foot in accordance with the variation in thickness of the work—*i. e.*, the layers of material constituting the sole, the edges of the upper, and the insole.

A further object of the invention is the improvement and simplification of presser-foot mechanism in machines of the class referred to for rendering them more certain and efficient in operation.

The manner in which I achieve the objects specified and in what the invention consists will be hereinafter fully set forth, it being sufficient for all general purposes to here state that the invention consists of a sewing-machine possessing certain features or characteristics of construction and arrangement of parts, as illustrated upon the accompanying drawings, described in the following specification, and particularized in the appended claims. I desire to have it understood, however, that I am in no wise limited to the particular mechanism which I have seen fit to illustrate and describe, although said mechanism is the best embodiment of the invention now known to me, for it will be apparent to those skilled in the art that the said mechanism may be varied in numerous ways without departing from the spirit and scope of the said invention.

Referring to the said drawings, Figure 1 represents in side elevation a machine embodying the invention. Fig. 2 represents a side elevation of the upper portion of the machine which is mounted or secured to the head. Fig. 3 is a view of the same through the other side. Fig. 4 represents a front end elevation of the mechanism shown in Figs. 2 and 3. Fig. 5 represents another view of the same with the parts in different positions. Fig. 6 is a perspective view of the front end of the machine. Figs. 7 and 8 represent a portion of the mechanism utilized for the automatic locking of the presser-foot. Fig. 9 represents a rear elevation of the upper portion of the machine, some of the parts being in section. Figs. 10, 11, and 12 illustrate a portion of the mechanism for starting and stopping the machine. Fig. 13 represents an enlarged section on the line 19 19 of Fig. 1. Fig. 14 represents an enlarged section on the line 20 20 of Fig. 1.

Referring to the drawings, 1 indicates a standard having a suitable base 2, the upper portion of the standard being bent rearwardly and then forwardly and flattened to receive the base-plate 3 of a head which is bolted or otherwise secured thereon. In the front of the standard provision is made for the reception of a rotatable horn 4, in which is mounted the usual looper mechanism and other devices ordinarily supported therein. I shall not attempt to describe the mechanism adjacent the horn more than to state that the driven parts are operated from a shaft 5, extending through the standard, as clearly shown in Fig. 1, and geared to the power-shaft in the head.

The head comprises the base-plate 3 and the uprights 6 and 7, in which there is journaled the power or needle-driving shaft 8, said shaft projecting rearwardly to receive the loosely-mounted pulley 9. Power is transmitted to said pulley by a belt 10 passing around a pulley 12, rigidly secured to a shaft 13, journaled in arms 14 15, rising vertically from a bracket 16, secured to the base 2 of the standard. Clutching mechanisms are inserted between the pulley 9 and the shaft 8

and the pulley 12 and the shaft 13, and I shall first describe the clutching mechanism on the shaft 13.

Referring more particularly to Figs. 1 and 5 13, it will be noted that the shaft 13 is longitudinally movable in the bearings afforded by the arms 14 and 15 and that the pulley 12 is rigidly secured by a screw to the shaft. Loosely mounted on the shaft are two belt-
10 pulleys 16 17, to which power is transmitted from a shaft 18 by belts 19 20 and belt-pulleys 21 22 on said shaft 18. The two belts 19 20 travel in the same direction; but the belt-pulley 21 is much larger in diameter than
15 that indicated at 22, so that when the pulley 16 is clutched to the shaft 13 the latter is rotated at much higher speed than when the pulley 17 is clutched thereto. To the outer faces of the pulleys 16 and 17 there are se-
20 cured disk-shaped friction members 23 24, respectively, with which friction members 25 26 may be engaged, according to the location of the shaft 13. The operative portions of the friction members 25 26 are shod with suit-
25 able friction material and said members are rigidly secured to the shaft, so that by moving the shaft to the right in Fig. 13 the friction member 25 will be engaged with the member 23, and if moved in the other direc-
30 tion the friction member 26 will be engaged with the member 24. The friction members may be constructed in other ways, if desired, although for ordinary purposes I find the form illustrated and described to be suitable. Be-
35 tween the friction members 25 and 23 I provide a comparatively strong spring 27, the ends of which bear against the member 25 and the middle portion of which bears against the member 23. This spring tends to hold
40 the members 26 and 24 in frictional engagement, and in order to overcome the tension of the spring for engaging the members 25 and 23 there is provided a bell-crank lever 28, fulcrumed on a stud 29, projecting from
45 the arm 14. On its upwardly-projecting end the bell-crank is equipped with a stud on which is journaled a frusto-conical idler 290, adapted to be moved into engagement with the beveled face of a ring 30, secured upon
50 the hub of the pulley 12 to move said pulley and the shaft 13 longitudinally of the axis of said shaft. The bell-crank lever is normally held in inoperative position by a spring 31, (see Fig. 14;) but it may be thrown into op-
55 erative position by foot-operated devices, including a foot lever or treadle 32, a rod 33, and a clip 34, adjustably secured to said rod by a set-screw 35. The treadle 32 is ful-
60 crumed upon a stud 36, projecting from the arm 15. The treadle may be depressed to a considerable extent without swinging the bell-crank 28 far enough to frictionally en-
65 gage the fast-moving pulley with the shaft 13, since the rod and lever are utilized for the purpose of starting the machine, as will be described. I provide relatively fast and slow moving pulleys, so that I may secure a va-

riable speed in sewing. Hence when sewing around the toe or heel the sewing mechanism will be actuated slowly, and while sewing along the shank or side I may throw the high-speed pulley into engagement with the shaft 18, so as to cause the rapid actuation of the sewing mechanism at such time. The two pulleys 16 and 17 rotate at different predetermined speeds, whereby the sewing mechanism is likewise actuated at different speeds, according to the portion of the shoe being stitched. This I regard as an important feature of the invention, since it enables the operator to note to a certainty the speed at which the mechanism is operating, thereby permitting him to guide the shoe accordingly, whether sewing at the toe or along the sides. It likewise permits the operator to change the speed of the machine instantly from slow to fast, and vice versa, during a single stitch with a knowledge of the speed to be thus instantly attained without considering the movement or inertia of the moving parts or waiting for the speed to change gradually, as where the ordinary speed mechanism is employed. The rod 33 is pivoted at its lower end (see Fig. 14) to the treadle 32 by a bolt 361, and at its upper end it is formed with a head 37, as shown in Figs. 3, 10, and 11, which is utilized in the starting and stopping mechanism, which I shall now proceed to describe.

On the shaft 8 and adjacent the pulley 9 is rigidly secured a disk 38, to which a pawl 39 is fulcrumed by a stud 40. (See Fig. 9.) The pawl overhangs a ratchet-wheel 41, rigidly connected with the pulley 9, and therefore loosely revoluble about the shaft 8. The pawl 39 is adapted to be drawn normally into engagement with the ratchet by a spring 42, having one end connected to the end of the pawl and the other end attached to a screw 43. The other end of the pawl is projected a short distance beyond the periphery of the disk 38, whereby it is adapted to be engaged by a pin 44, projecting from a stud 45 in the end of an elbow-lever 46, fulcrumed on a pin 47, projecting from a lug 48 on the standard 1. One arm of the elbow-lever projects upwardly and the other forwardly at right angles thereto, being provided with a notched clip 49, with which the head 37 may be engaged. The said head 37 is provided with two shoulders which are separated, so that when the treadle 32 is operated the elbow-lever is likewise actuated; but there is a certain amount of lost motion between the head 37 and the clip 49. This lost motion permits the treadle to be depressed to throw in or out the fast-speed pulley without releasing the elbow-lever, as will be explained. A spring 50 (see Fig. 3) is utilized to hold the pin 44 normally in the path of the end of the pawl 39. As long as the treadle is undepressed the pin 44 remains in engagement with the end of the pawl and holds it free from the ratchet 41, whereby the pulley 9 rotates without causing the rotation of the shaft 8. When

the treadle is depressed, the pin 44 is moved axially of the shaft 8 to release the pawl and permit it to engage the ratchet 41. The elbow-lever 46 is adapted to be held in an inoperative position by a locking-pawl 51, pivoted upon a stud 52 and drawn into engagement with the clip 49 when the latter is depressed by a spring 53. Said pawl is provided with a pin 54, with which a cam edge 55 on the head 37 engages when the rod rises and releases the pawl from the clip 49 to permit the pin 44 to return to its operative position under the impulse of the spring 50. In addition to the pin 44 the elbow-lever carries a spring-tensioned stop adapted to stop the rotation of the shaft 8. Said stop is indicated at 56, and it has a downwardly-projecting spring-arm 57, which tapers toward its end. The said end is held between two pins 58, extending into the upwardly-projecting arm of the elbow-lever 46. Said stop 56 when the said elbow-lever is in operative position extends into the path of a stop on a disk 59, said stop being formed by cutting away said disk, so as to leave a shoulder 58^x. (See Fig. 12.) When the shoulder 58^x engages the stop 56, the jar and the reaction are both taken up by the spring-arm 57.

With this description it will be seen that at the instant the pulley 9 is unclutched from the shaft 8 the said shaft is stopped from rotation and that said shaft will be stopped after each rotation unless the foot-treadle is depressed. The separation of the shoulders on the head 37 permits the head to rise, while the lever is locked by the pawl 51 until the latter is thrown out by the pin 54, and hence the elbow is released very rapidly, and it quickly snaps into position in time to stop the machine at the completion of the stitch.

I propose to now describe the presser-foot, which is automatically adjusted according to the thickness of the work, and the mechanism for automatically locking said presser-foot after it has been adjusted. Said presser-foot is indicated at 60 and is located above the end of the horn 4 and a little to one side of the axis of rotation thereof. Said presser-foot is adjustably secured to a vertically-movable bar 61, which has a downwardly and laterally projecting finger 62. The presser-foot is pivoted upon a stud 63 and is adapted to be held at any desired adjustment by a set-screw 64. (See Figs. 2 and 4.) The bar 61 projects vertically upward, and it is mounted in guides, being provided at its upper end with a slot 65, through which a screw-pin 66 passes into a bracket 67, bolted at the top of the upright 6. The lower end of said bar is guided by a flanged plate 68, affixed to the side of the base-plate 3. An adjusting-screw 69 (see Fig. 4) is passed downwardly through the top end of the bar 61, and its end rests upon the pin 66 when the presser-foot is in its lowermost position. Near the bed-plate the bar 61 is formed with a shoulder 70, and to the side of the bar above the shoulder there is

secured a clip 71, having a shoulder confronting that at 70. Between the shoulders there is a space afforded for the reception of a pin 72, by means of which the presser-foot may be raised or lowered or locked in position, as the case may be. The said pin 72 projects forwardly from an arm 73, which is rigidly secured to a shaft 74, journaled in bearings 75 afforded by the uprights of the head. There is a spring 75 coiled around the shaft 74 with one end secured to a collar 76, affixed to the shaft by a set-screw 77, and with the other end resting against the top of the bed-plate 3, 80 and said spring normally holds the presser-foot downward, so as to rest upon the sole of the shoe on the horn. Said spring, however, is not so strong but that it permits the presser-foot to rise and fall according to the thickness of the work as the latter is fed along, so as to always rest upon the top of the sole. The arm 73, from which the pin 72 projects, has a projection 78 in the path of a lever 79, centrally fulcrumed upon a stud 80, 90 and having its rear end connected by a rod 81 to a treadle 82, fulcrumed upon the stud 36, which projects through the upright 15 at the base of the machine. When the operative depresses the said treadle 82, the presser-foot is 95 raised to permit the insertion of the shoe upon the horn. The mechanism for automatically locking the presser-foot after the feeding of the shoe comprises an arm 83, the hub 84 of which is rigidly secured to the shaft 74. On its 100 end the arm has a segmental extension 85, as shown in Figs. 5 and 7. Loosely mounted on the shaft 74 is a lever having two arms 86 87, the latter being substantially parallel to the bed-plate and being held down by a spring 88, 105 coiled around a pin 89, passed loosely through the arm into the bed-plate. The end of the arm 86 forms one jaw of a clamp, the other jaw being the end of a resilient or spring lever 90, fulcrumed upon a screw-pin 91, 110 passed therethrough into a boss 92 on the arm 86. The segmental extension 85 of the arm 83 passes between the two jaws and is adapted to be clamped thereby when the lower end of the lever 90 is moved toward the back end of 115 the machine. To cause the operation of the clamp, there is a cam 93, rigidly secured upon the shaft 8. Said cam has a cam-rim 94 and also a cam 95, with a single depression 96. The cam-rim 94 has also a single depression, 120 as shown in Fig. 7. A lever 97 is fulcrumed upon a stud 98, passed into a bracket 99 on the bed-plate, (see Fig. 8,) and it projects at an inclination across the base-plate, being equipped on its end with a roller 100, resting 125 against a cam-rim 94. Passed through the arm 86 is a pin 101, which rests against the side of the lever 97, and the other end of the pin is formed with a reduced end projecting through an aperture 102 in the lever 90 and 130 with a shoulder which bears against the inner face of said lever. The cam-rim normally holds the clamp in its operative position, and the lever 83 is released only for an

instant immediately after the feeding of the work to permit the presser-foot to rise or fall with the surface of the sole as the thickness varies, after which it is again immediately 5 locked. The lever 86 has a roll 103 resting against the cam 95, whereby the arm or lever 86 is rocked to permit the feeding of the work. The lever 86 is rocked by the cam after the clamp engages the segmental extension 85 for 10 lifting the presser-foot to permit the feeding of the work, which takes place again subsequently. The parts of the machine are so timed that the roll 100 enters the depression in the cam-rib 94 just as the end of the lever 15 39 comes to a point where it may be engaged by the pin 44, as shown in Fig. 7, whereupon the machine is stopped, and the operative may rock the part or arm 73 by means of the treadle 82 to raise the presser-foot.

20 Through the arm 87 there is passed an adjusting-screw 500, which bears against the bed-plate, which may be locked in position by the nut 501. This screw regulates the operation or movement of the lever 86, since it adjusts the roll 103 toward or from the cam 95, and thereby determines the length of contact 25 between the last-mentioned parts. Consequently it varies the extent to which the presser-bar is lifted during the feeding of the 30 work.

According to this description I provide a member which is positively connected to the presser-foot and which may be clamped to hold the presser-foot against movement. The 35 illustrated embodiment of the invention shows the member as consisting of two parts 73 and 83, connected by a rock-shaft, the longer one of which is in the nature of an arm of a lever. The parts 73 and 83 constitute, as it were, the short and long arms, respectively, of a bell-crank lever, the rock-shaft thus being a fulcrum or pivot. The short arm is connected to the presser-foot and the long arm is adapted to be engaged 40 near its end by the spring friction clamping mechanism. The difference in length between the two arms is an important factor in determining the force necessary to lock the presser-foot against movement.

45 50 That part of the sewing mechanism which is mounted upon the head and which I denominate the "upper" sewing mechanism comprises a needle, its actuating mechanism, and a cast-off. The needle is shown at 105, and it is clamped in the lower end of a vertically-reciprocating needle-bar 106 by a clamp 107. The bar reciprocates vertically in guides mounted in the bracket 67 and in an extension of the bed-plate 3.

55 60 The cast-off is indicated at 123, and it is secured upon the end of a narrow bar 124, slidably secured in a groove in the needle-bar 106. At its upper end it projects from the slot, as shown at 125, and is connected by a spring 65 126 with the collar 112. There is another collar 127 around the needle-bar between the projecting end 125 and the top of the collar 112.

Said collar is provided with an upwardly-extending arm 128, which passes between the bracket 67 and friction material 129, held 70 against the arm by a clip 130. The needle-bar has secured to it a stud a short distance from the collar 112, so that the cast-off has a certain amount of lost movement at each reciprocation of the needle-bar. The 75 cast-off performs the ordinary function accomplished by such devices, and it is properly timed, as will be subsequently described.

The feeding mechanism comprises a point 131, secured in an arm 134, connected by a 80 stud 132 with the lower end of a bar 133. The arm and point are free to swing upwardly on the reverse lateral movement of the bar, but are held against so doing during the forward movement by a pin 135 engaging a shoulder 85 at the lower extremity of said bar 133. The bar has an up-and-down as well as an oscillatory movement. At its upper end there is a stud 136 passing through a slot 137 in the presser-foot bar, said stud being equipped 90 on its end with a roll 138. There is another stud 139 above it, on which there is a roll 140, said stud 139 being secured to the presser-foot bar.

The operation of the machine is as follows: 95 The operative having placed a shoe upon the horn, after raising the presser-foot by means of the treadle, as described, the presser-foot descends upon the work, the feeding-point also engaging the latter. The point and the 100 presser-foot remain stationary while the needle descends, and the looper (not shown, but placed in the horn) carries the thread around it, the cast-off mechanism following the needle until it strikes the work, whereupon said cast-off stops and the needle penetrates the work to receive the loop. As the 105 needle rises it slides by the cast-off until the barb of the needle is covered, and then the cast-off rises with the needle-bar. Just as the 110 needle starts to lift the presser-foot is raised slightly, and as the needle leaves the work the feeding-point moves forward. By the 115 time the needle has reached its highest point the feeding-point has reached the limit of its travel. The presser-foot is let down by the cam and is released by the locking mechanism to permit it to adjust itself to the thickness of the work, said presser-foot adjusting itself at every stroke of the needle, as previously 120 described. The movement of the presser-foot causes the adjustment of the movable fulcrum previously described, thus arranging for the length of the upward travel of the needle for the next loop. Immediately after the presser-foot is positioned it is clamped to form an 125 abutment for the work and to hold the fulcrum rigidly against movement. The feeding-point is lifted out of the work and is drawn back to its first position, the needle now being 130 at its highest point, with the loop held in the barb by the cast-off. When the needle descends, the loop is held by the cast-off and the next stitch is drawn up through it. The

stop mechanism, as previously described, is so arranged that the machine stops after one rotation of the shaft 8 unless the clutch is held out of operation by the treadle. The 5 cam 95 holds the presser-foot raised slightly during the feeding operation to prevent its dragging on the work.

It will be seen that I have provided a compact and easy-running machine. The needle-10 driving shafts extend longitudinally of the bed and in parallelism with the various rock-shafts which cause or govern the action of the other operative parts of the mechanism. The movable fulcrum, with which the needle-bar 15 is engaged or connected only during the up-stroke thereof, and the greater part of the controlling mechanism therefor are located between the needle-bar-driving shaft and between the needle-bar and the upright on the 20 bed. The adjustable parts have means for positively adjusting them to predetermined position, and the whole machine is neater, more compact, and more efficient than those heretofore constructed. By the employment 25 of friction clamping mechanism I am enabled to lock the presser-foot at the exact position to which it has been adjusted by the work without any lost motion. Consequently I am able to adjust the variable fulcrum with the 30 greatest accuracy for the length of the loop, a thing that has been impossible when positive mechanism, such as a pawl and ratchet, has been used for locking the presser-foot after its adjustment by the work. This I regard as an important feature of the invention, 35 for I believe that I am the first to have employed friction clamping mechanism for the purpose specified. In connection with the clamping mechanism it will be observed that 40 the lever 83, which has the segmental extension, is much longer than the arm 73, and hence I secure a greater leverage in clamping the presser-foot and attain a more accurate clamping of the latter.

45 This application is a division of my co-pending application, Serial No. 21,084, filed June 21, 1900, for shoe-sewing machine.

Having thus explained the nature of the invention and described a way of constructing 50 and using the same, although without attempting to set forth all of the forms in which it may be made or all of the modes of its use, I declare that what I claim is—

1. A machine of the character described 55 having a presser-foot varied in position by the thickness of the work, a bar or support on which the presser-foot is mounted, a member connected to the presser-foot bar, and means for clamping said member and thereby with 60 a minimum of pressure holding said presser-foot against movement.

2. A machine of the character described 65 having a presser-foot varied in position by the thickness of the work, a bar or support on which the presser-foot is mounted, a member connected to the presser-foot bar and having an elongated arm, and friction mechanism

for clamping said arm and thereby locking said presser-foot against movement.

3. A machine of the character described 70 having a presser-foot varied in position by the thickness of the work, a bar or support on which the presser-foot is mounted, a member connected to the presser-foot bar, and means for clamping said member and thereby with 75 a minimum of pressure holding said presser-foot against movement, said means comprising two clamping members of which one is a lever fulcrumed near one end to secure a greater leverage in clamping the said member. 80

4. A machine of the character described 85 having a presser-foot varied in position by the thickness of the work, a member consisting of a short arm connected to the presser-foot, and a relatively long free arm, and means for clamping said long arm and thereby locking 90 said presser-foot against movement.

5. A machine of the character described 95 having a presser-foot varied in position automatically by the thickness of the work, a bar 100 or support on which the presser-foot is mounted, a member connected to the presser-foot bar and having an elongated arm, and an automatic clamp for engaging said arm.

6. A machine of the character described 105 having a presser-foot varied in position automatically by the thickness of the work, a bar or support on which the presser-foot is mounted, a member connected to the presser-foot bar, a clamp for holding said member and 110 thereby the presser-foot against movement, and a cam controlling the actuation of said clamp.

7. A machine of the character described 115 having a presser-foot, a member connected therewith, an automatic clamp for locking said member to hold said presser-foot against the work, means for bodily moving said clamp and member to lift the presser-foot from said work, and means for regulating the movement of the clamp.

8. A machine of the character described 120 having a presser-foot, a member connected to said presser-foot, an automatic spring friction-clamp for yieldingly engaging and clamping said member and thereby holding the presser-foot, and means for closing said clamp.

9. A machine of the character described 125 having an automatically-adjustable presser-foot, a bar or support on which the presser-foot is mounted, a power-shaft, clamping mechanism for said presser-foot comprising a member connected to said presser-foot bar, a clamp for clamping the member, and a cam on said shaft for operating the clamp.

10. A machine of the character described 130 having an automatically-adjustable presser-foot, a power-shaft, a clamp for said presser-foot provided with two coacting members, a cam on said shaft for positively closing said clamp, and thereby holding the presser-foot against movement relatively thereto, and a supplemental cam for moving said clamp

bodily to lift the presser-foot and permit the feeding of the work thereunder.

11. A machine of the character described having an automatically-adjustable presser-foot, a member connected to said foot, a power-shaft, a clamp having separable friction members for clamping said foot member and thereby holding said presser-foot after adjustment, one of said friction members being yielding, and mechanism actuated by said power-shaft for contracting said members to clamp the said foot member.

12. A machine of the character described having an automatically-adjustable presser-foot, a rocking member connected with said presser-foot and having an arm, automatic mechanism for clamping said arm after the presser-foot is adjusted, and automatic means for rocking said member.

13. A machine of the character described having an automatically-adjustable presser-foot, a rock-shaft having a short arm connected with the presser-foot and a relatively long arm, and automatic mechanism for clamping said long arm.

14. A machine of the character described having an automatically-adjustable presser-foot, a lever connected meditately with the presser-foot and having a lateral segmental extension, and automatically-actuated

clamping members between which said extension projects and by which it is intermittently clamped.

15. A machine of the character described having an automatically-adjustable presser-foot, a lever connected meditately with the presser-foot, a movable clamp having separable members adapted to engage said lever, automatic means for closing the clamp, and automatic means for moving said clamp to raise the presser-foot.

16. A machine of the character described comprising a presser-foot resting on the surface of the work and adjusted automatically thereby, mechanism for locking said presser-foot in operative position, and a stop mechanism controlling the operation of the machine, said parts being arranged and operated whereby the presser-foot is automatically released when the stop-motion is actuated to stop the machine, whereby the said presser-foot is then free to be moved manually.

In testimony whereof I have affixed my signature in presence of two witnesses.

EVERETT P. RICHARDSON.

Witnesses:

WILLIAM J. DELANEY,
MATTHEW A. CREGG.
